I. WEISS.
DRAPERY SUPPORT.
APPLICATION FILED SEPT. 8, 1915.

Patented Nov. 28, 1916.

UNITED STATES PATENT OFFICE.

IZIDUR WEISS, OF NEW YORK, N. Y.

DRAPEY-SUPPORT.

1,206,489.

Specification of Letters Patent. Patented Nov. 28, 1916.

Application filed September 8, 1915. Serial No. 49,481.

To all whom it may concern:

Be it known that I, IZIDUR WEISS, a citizen of the United States, and a resident of New York, county and State of New York, have invented a certain new and useful Improvement in Drapery-Supports, of which the following is a full, clear, and exact specification.

This invention relates more particularly to a class of devices adapted to be used in conjunction with draperies.

My invention has for its object primarily to provide a support designed to be employed for permitting curtains, lambrequins, portières, and other draperies to be easily suspended at the windows, doorways, and other places in buildings and elsewhere, and which is of an adjustable form so that the support may be removably mounted in windows and doorways of various widths as well as being of a form whereby draperies of different kinds may be removably supported at a single window, or doorway. This is accomplished mainly by providing a rigid member, or bar of a desired length so as to be disposed between the stiles of the frame of a window, or doorway, or other spaced supports, and on one end of the bar is a stationary retaining element adapted to engage one of the supports to removably hold this end of the bar thereto. On the other end of the bar is an adjustable retaining element adapted to be moved into engagement with the second support when the retaining element is adjusted accordingly for removably holding the other end of the bar to the support.

Other objects of the invention are to provide on one side of the bar means whereby curtains may be detachably suspended therefrom; to provide on the opposite side of the bar means to permit a lambrequin, or other drapery to be detachably applied thereon; and to provide a drapery support of a simple, efficient and durable construction.

A practical embodiment of the invention is represented in the accompanying drawing forming a part of this specification in which similar characters of reference indicate corresponding parts in all the views, the said invention being more fully described herein-after, and then pointed out in the claim at the end of the description.

In the drawing, Figure 1 is a sectional view taken vertically through a window showing the manner of using one form of

drapery support embodying my invention in conjunction therewith. Fig. 2 is a top plan, partly broken away, of the support. Fig. 3 is an end view of the support. Fig. 4 is a sectional view, partly broken away and partly in detail, taken on the line IV—IV of Fig. 3, and Fig. 5 is an enlarged fragmentary side view, partly in section, of part of the retaining element used in the support.

The device, or drapery support has a rigid member, or bar 10 which may be of any suitable size and shape, though the bar is preferably substantially rectangular, as viewed transversely. The underside of the rectangular bar 10, at one end thereof is recessed, at 11, and also in this underside of the bar adjacent to this recess is a second recess 12. Vertically through the bar 10, and adjacent to the second recess 12 is an opening 13. Through the partitions, or parts, as 14, of the bar between the recesses 11 and 12 is an orifice 15, while through the partition, or part, as 16, between the recess 12 and the opening 13 is an orifice 17 which is in register with the orifice 15, and the recess 12 is bridged by a plate 18 which is screwed, or bolted to the lower ends of the partitions 14 and 16. On one end of the bar 10 is a stationary retaining element, as 19, adapted to engage a support to removably hold this end of the bar thereto, and on the other end of this bar is an adjustable retaining element, as 20, adapted to engage a second support for removably holding the other end of the bar when the device is in use, as will be hereinafter more fully explained.

The stationary retaining element 19 is preferably in the form of two pins 21 and 22 having pointed ends, and these pins extend from spaced parts of a plate 23 which is secured by any suitable means on one end of the bar 10. The adjustable retaining element 20 has a plate 24 disposed transversely in the recess 12 of the bar 10, and this plate is screwed, or bolted to the bar so as to be fixed thereto. Through the plate 24 is a threaded hole 25 which is in register with the orifices 15 and 17 of the partitions 14 and 16 of the bar 10. Screwed through the opening of the plate 24, and rotatably disposed through the orifices 15 and 17 of these partitions is a threaded rod 26 of a length to extend from the center of the opening 13 through the recess 12 and outwardly of the recess 11. On the end of the rod 26 in the opening 13 is a handle, or

wheel 27 having a number of radially disposed spokes, as shown, to permit the rod to be readily rotated for being guided inwardly and outwardly of the recess 11 with 5 relation to the second end of the bar 10. In the end part of the rod 26 opposite to the handle 27 is an annular groove 28, and revolubly movable in this groove is a plate 29 from spaced intervals of which extend 10 pins 30 and 31 having pointed ends.

Serving as means to permit curtains and the like to be detachably suspended from the bar 10, projecting from spaced parts of one of the side edges of the bar 10 may be two 15 alined apertured brackets, or eyes, as 32 and 33, of well-known forms, and in the apertures of these brackets is removably disposed a rod 34.

In order to permit a lambrequin, or other 20 drapery to be also detachably suspended from the bar 10, on the top of the bar at its second side edge is a strip, or flange 35 having a number of spaced pins 36 projecting upwardly therefrom, and these pins 25 have pointed free ends.

When the device is employed for suspending draperies, such as curtains, as 37, and a lambrequin, as 38, at a window, as 39, the rigid member, or bar 10 is disposed between 30 the upper part of the stiles of the frame 40 of the sash of the window. The pins 21 and 22 of the retaining element 19 are then forced into one of the stiles, and the handle 27 of the rod 26 of the retaining element 20 is 35 rotated to guide the rod for moving the plate 29 together with the pins 30 and 31 outwardly of the recess 11 of the supporting bar 10 for causing these pins to penetrate the second stile of the window frame. 40 The device will thereby be removably supported at the window. To allow one, or more curtains to be suspended from the device the rod 34 is removed from the apertured brackets 32 and 33, and this rod is 45 passed through a passage provided by hemming the upper end of each curtain. The rod 34 is then remounted in the apertured brackets 32 and 33, and the curtains are afterward draped in the manner desired. 50 A lambrequin, or other drapery may subsequently be suspended from the device by attaching the upper part thereof on the pins

36 projecting upwardly from the bar 10, the arrangement of these pins permitting a neat arrangement of the drapery, or an easy 55 application of the lambrequin to the device following the previous formation thereof in the style desired. In this manner a simple, efficient, and durable support is provided for permitting draperies to be readily suspended at windows, doorways, and other places in buildings and elsewhere, and by providing the adjustable retaining element 60 20 of the form described the device is susceptible of being removably mounted in 65 windows and doorways of various widths by reason of this retaining element serving to compensate for shortage of the bar 10.

In the foregoing description, I have embodied the preferred form of my invention, 70 but I do not wish to be understood as limiting myself thereto, as I am aware that modifications may be made therein without departing from the principle, or sacrificing any of the advantages of this invention, 75 therefore I reserve to myself the right to make such changes as fairly fall within the scope thereof.

Having thus described my invention, I claim as new and desire to secure by Letters 80 Patent:-

In a drapery support, a bar adapted to be disposed between two supports, stationary pointed pins on one end of the bar, adapted to be forced into engagement with 85 one of the supports for holding one end of the bar, a rod rotatable on the other end of the bar so as to be extensibly adjusted relative to this end of the bar, and the rod having pointed pins projecting therefrom to 90 engage the second support when the rod is adjusted accordingly for holding the second end of the bar to the support, a rod removably mounted on the bar to permit drapery to be detachably suspended therefrom, and 95 pointed pins also on the bar to allow other draperies to be detachably suspended from the bar.

This specification signed and witnessed this seventh day of September, A. D. 1915. 100
IZIDUR WEISS.
